UNITED STATES PATENT OFFICE.

FRANK M. BROOKS, OF NEW YORK, N. Y.

DESIGN FOR AN INVERTED GAS-BURNER.

No. 39,567.

Specification for Design.

Patented Sept. 22, 1908.

Application filed July 7, 1908. Serial No. 442,438. Term of patent 7 years.

To all whom it may concern:

Be it known that I, FRANK M. BROOKS, a citizen of the United States, and a resident of the borough of Brooklyn, county of Kings, city and State of New York, have invented a new and original and ornamental Design for Inverted Gas-Burners, of which the following is a specification, reference being had to the accompanying drawing, forming part thereof.

The figure is a perspective view of an inverted gas burner showing my new design.

I claim—

The ornamental design for an inverted gas burner as shown.

FRANK M. BROOKS.
